UNITED STATES PATENT OFFICE

148,735

DESIGN FOR A COFFEE ROASTING MACHINE

August S. Torres, Kinderhook, N. Y.

Application April 9, 1946, Serial No. 128,408

Term of patent 3½ years

(Cl. D55—1)

To all whom it may concern:

Be it known that I, August S. Torres, a citizen of the United States, residing at Kinderhook, in the State of New York, have invented a new, original, and ornamental Design for a Coffee Roasting Machine, of which the following is a specification, reference being had to the accompanying drawing, forming part thereof.

In the drawing:

Fig. 1 is a side elevational view of a coffee roasting machine showing my new design.

Fig. 2 is a front elevation.

Fig. 3 is a rear elevational view.

Fig. 4 is a plan view.

I claim:

The ornamental design for a coffee roasting machine, as shown.

AUGUST S. TORRES.
